UNITED STATES PATENT OFFICE.

WILLIAM S. DAVENPORT, OF NEW BEDFORD, MASSACHUSETTS, ASSIGNOR TO MORSE TWIST DRILL & MACHINE COMPANY, OF NEW BEDFORD, MASSACHUSETTS, A CORPORATION OF MASSACHUSETTS.

TRUING-TOOL HOLDER FOR GRINDING-MACHINES.

1,110,424.

Specification of Letters Patent.

Patented Sept. 15, 1914.

Application filed April 18, 1910. Serial No. 556,047.

To all whom it may concern:

Be it known that I, WILLIAM S. DAVENPORT, a citizen of the United States, residing at New Bedford, in the county of Bristol and State of Massachusetts, have invented certain new and useful Improvements in Truing-Tool Holders for Grinding-Machines; and I do hereby declare the following to be a full, clear, and exact description of the invention, such as will enable others skilled in the art to which it appertains to make and use the same.

The invention relates to devices for truing the grinding wheels of plain or universal grinding machines such as are used for grinding cylindrical surfaces, and in which the work is supported upon centers and rotated while the point of operation of the grinding wheel is transferred along the work by reciprocation of either the grinding wheel or the work support.

During the operation of machines of this character the surface of the grinding wheel frequently becomes glazed or untrue, so that it is necessary to cut away the surface of the wheel by means of a diamond point or truing tool in order that the wheel may operate properly upon the work. The devices which have heretofore been employed for holding or supporting the truing tool have been so constructed and arranged that it has been necessary to either remove the work from the centers, readjust the machine so as to allow an increased travel of the work support past the wheel, or to move the wheel out of grinding relation with the work, and with certain constructions all of these changes or adjustments must be made in order to true the grinding wheel. After the wheel has been trued the parts must be then readjusted to bring the wheel and work into proper grinding relation, and to secure the proper relative travel of the work and wheel. These changes in the adjustments of the machine render the truing of the wheel inconvenient, and also involve a loss of time and consequent reduction in the production of the machine.

It is accordingly the object of the pres-

ent invention to provide means for truing the grinding wheel without removing the work from the centers or materially changing the adjustment of the machine. To this end the invention contemplates the provision in a grinding machine for grinding cylindrical work of a truing tool holder having provision for engaging the truing tool with the grinding wheel while the grinding wheel is in grinding relation to the work. With this construction the truing tool may be engaged with the grinding wheel while the work is still supported upon the centers, and without disturbing the adjustment of the devices which control the relative travel of the work and grinding wheel, and without any adjustment of the grinding wheel carriage. The tool may then be caused to travel across the surface of the wheel, and adjusted to cut away and true its surface. After the wheel has been trued, it is merely necessary to advance the grinding wheel to the work to compensate for the amount it has been trued, and then go on with the grinding operation. The specific construction and arrangement of the truing tool holding device is not material to the invention in its broader scope. In the simplest and most efficient form of the invention which I have yet devised, however, the truing tool is secured in a carrier which may be readily swung into and out of working position without disturbing the work or the adjustment of the grinding wheel, and which is provided with an adjusting or operating device for regulating the action of the tool upon the wheel.

The various features of the invention will be readily understood from the accompanying drawings and the following detailed description of the construction shown therein.

In the drawings Figure 1 is a plan view illustrating so much of a plain grinding machine as is necessary to show the application of the present invention thereto; Fig. 2 is a transverse sectional elevation showing the devices for holding the truing tool in elevation; and Fig. 3 is a sectional detail of the truing tool carrier.

The machine shown in the drawings is a plain grinding machine for grinding cylindrical or tapered work. In this machine the work 1 is supported upon centers carried by the head-stock 2 and tail-stock 3 which are adjustably secured upon ways formed on the swivel table 4. The swivel table is mounted in the usual manner upon a bed 5 which is reciprocated to transfer the point of operation of the grinding wheel 6 along the work. The grinding wheel is mounted in a carriage 7 which is moved transversely to bring the grinding wheel into grinding relation to the work, and to feed the wheel forward as the grinding operation progresses. The parts thus far described may be of any well-known construction, and coöperate in the usual and well-known manner to effect the grinding.

20 The devices for truing the grinding wheel consist of a carrier 8 in which a diamond tool 9 of the usual construction is rigidly secured by a clamping screw 10. The tool carrier is mounted upon the work supporting table 4 in such manner that the tool may be readily brought into engagement with the grinding wheel, or may be moved back out of working position. As shown, the carrier is pivoted at 11 to a base 12 which is secured upon the ways 13 by a clamping plate 14 and bolt 15. The base 12 is provided with an arm 16, and the tool carrier is provided with an adjusting screw 17 adapted to engage the upper side of the arm when the carrier is swung into working position.

30 During the grinding operation the tool carrier is swung back into the position indicated in full lines in Figs. 1 and 2 where it is out of working position. When it is desired to sharpen or true the grinding wheel the tool carrier is swung forward into the position indicated in dotted lines in Fig. 2. The pivot 11 for the carrier is so arranged that the truing tool extending over the work and into position to engage the wheel, while the wheel is still in working relation to the work. The parts are also so proportioned and arranged that the point of the truing tool lies above the line drawn between the center of

40 the pivot 11 and the center of the grinding wheel. By turning the adjusting screw 17, therefore, the point of the truing tool may be moved toward or away from the surface of the grinding wheel to regulate the action of the tool upon the wheel and to cause the tool to cut away the surface of the wheel to the desired extent. While the truing tool is in engagement with the surface of the grinding wheel the bed 5 may be reciprocated manually or by power, the movement of the bed in the latter case being reversed by the operator to carry the truing tool back and forth across the surface of the wheel. After

the wheel has been trued the truing tool carrier may be swung back into the full line position in Fig. 2. The grinding wheel is then advanced slightly to bring its surface against the work, and the grinding is continued. The grinding wheel may thus be quickly and conveniently trued or sharpened without removing the work or altering the adjustment of the reversing mechanism for the bed, and without requiring any material alteration in the adjustment of the grinding wheel. The time lost in truing the grinding wheel is thus reduced to a minimum, with a corresponding increase in the production of the machine.

While it is preferred to employ the specific construction and arrangement of the parts shown and described, it will be understood that this construction is not essential, and may be varied and modified without departing from the broader scope of the invention.

Having explained the nature and object of the invention, and specifically described one construction in which it may be embodied, what I claim is:—

1. A mechanism for truing the wheels of grinding machines, having, in combination, a grinding wheel support and work supporting table relatively movable to transfer the point of operation along the work, work carrying centers on the work table and a truing tool holder having provision for engaging the truing tool with the grinding wheel while the grinding wheel is in grinding relation to the work carried by the centers whereby the wheel may be trued without removal of the work or variation in the adjustment of the machine.

2. A mechanism for truing the wheels of grinding machines, having, in combination, a grinding wheel support and work supporting table relatively movable to transfer the point of operation of the grinding wheel along the work, work carrying centers on the work table, a truing tool carrier mounted on the work table, and means for adjusting the tool to true the wheel while the wheel is in grinding relation to the work carried by the centers.

3. A mechanism for truing the wheels of grinding machines, having, in combination, a grinding wheel support and work supporting table relatively movable to transfer the point of operation of the grinding wheel along the work, work carrying centers on the work table, a truing tool carrier on the work supporting table mounted for movement into and out of working position, and means for actuating the carrier to move the truing tool toward or from the grinding wheel when the carrier is in working position.

4. A mechanism for truing the wheels of grinding machines, having, in combination,

a base, means for securing the base to the work supporting table of the grinding machine, a truing tool carrier on the base movable into and out of working position over the work supported on the work carrying centers of the table, and an actuating device for operating the carrier to move the tool toward or from the grinding wheel when the carrier is in working position.
